[57] CLAIM

The ornamental design for a fluid dispenser tee tower, as shown and described.

DESCRIPTION

FIG. 1 is an upper-end and angled perspective view of the design feature for a fluid dispenser tee tower; the broken line depiction of a tap handle in this and other figures being for illustrative purposes only and forming no part of the claimed design.

FIG. 2 is a right side perspective view thereof;

FIG. 3 is a left side perspective view thereof;

FIG. 4 is a front view perspective view thereof;

FIG. 5 is a rear view perspective view thereof;

FIG. 6 is a top view perspective view thereof; and,

FIG. 7 is a bottom view perspective view thereof.
